ABSTRACT: A first serial connection comprises a first resistor, a first composite transistor and a first load. A second serial connection comprises a second load, a second composite transistor, a second resistor, a third load and a third resistor which is connected in the circuit of the second composite transistor. An output voltage of a magnitude larger than the magnitude of the voltage drop due to an input current is obtained.

ELECTRIC CURRENT-VOLTAGE CONVERTING CIRCUIT

BACKGROUND OF THE INVENTION

This invention relates to a current-voltage converting circuit and more particularly to a current-voltage converting circuit in which a resistor is inserted in a composite transistor circuit used for this current-voltage converting circuit in the current-voltage converting circuit of a direct current operational circuit in which one of the terminals of a plurality of loads or operational circuits is connected to the fixed potential of a power source.

SUMMARY OF THE INVENTION

In the invention of subject invention, a first serial circuit comprised of a first resistor, a first composite transistor and a first load is connected across a constant current source and a second serial circuit comprised of a second load, a second composite transistor, a second resistor, a third load and a third resistor is connected across a current source. The first resistor and the first composite transistor are connected parallel to the second resistor and the second composite transistor. The resistor is connected in the circuit of the second composite transistor. When the voltage across the base electrode and the emitter electrode of the first composite transistor is made substantially equal to the voltage across the base electrode and the emitter electrode of the second composite transistor, an output voltage of a magnitude larger than the magnitude of the voltage drop due to an input current can be obtained across the second resistor and the third resistor.

Therefore, the object of this invention is to obtain a current-voltage converting circuit which is capable of supplying current to the above loads simultaneously.

Another object of this invention is to obtain a current-voltage converting circuit which is capable of getting a voltage output larger than the voltage drop due to the input current.

The current-voltage converting circuit of this invention can be used also as a current converting circuit.

BRIEF DESCRIPTION OF THE DRAWING

FIGS. 1 through 4 are the connection diagrams showing the electric current converting circuits which are the basis for the current-voltage converting circuit of this invention and variations of the basic circuits; and

FIG. 5 is a connection diagram showing an embodiment of the current-voltage converting circuit of this invention.

DESCRIPTION OF THE PREFERRED EMBODIMENTS

In FIG. 1, the emitter of a PNP-type transistor Q_1 is connected to a terminal 1 and the base of an NPN-type transistor Q_2 through a resistor R_1 and the emitter of the transistor Q_2 is connected to a terminal 4 and the base of the transistor Q_1 through a resistor R_2 .

The collector of the transistor Q_1 is connected to the negative terminal of a constant current source 11 and the negative terminal of a power source E_2 through a terminal 2 and a load or an operational circuit Z_1 , and the positive terminal of constant current source 11 is connected to terminal 1.

The collector of the transistor Q_2 is connected to the positive terminal of a power source E_1 through a terminal 3 and a load or an operational circuit Z_2 , and the negative terminal of the power source E_1 is connected to the positive terminal of a power source E_2 and a terminal of a load or an operational circuit Z_3 . The other terminal of the load Z_3 is connected to terminal 4 and the joint between the emitter of the transistor Q_2 and the resistor R_2 forms a terminal 5.

The circuit surrounded by terminals 1, 2, 3 and 4 is named a four-terminal network N. The resistors R_1 and R_2 perform the function to determine the conversion characteristics.

In the circuit of FIG. 1, if constant current source 11 generates a current I_1 in the direction shown in the FIG. a voltage V across terminals 1 and 4 is represented by

$$V = I_1 R_1 + V_{be1}$$

where, R_1 = resistance of resistor R_1

5 V_{be1} = voltage across base and emitter of transistor Q_1 .

The transistors Q_1 and Q_2 have both high gains and the base current is small compared with the collector current; and therefore it is possible to assume that the collector current of the transistor Q_1 is equal to the current I_1 .

If a current supplied from the battery E_1 to the circuit consisting of the load Z_2 , the transistor Q_2 , the resistor R_2 and the load Z_3 is represented by a current I_2 , similarly the voltage V across terminals 1 and 4 is shown by the following formula.

$$V = V_{be2} + I_2 R_2$$

where, V_{be2} = voltage across base and emitter of transistor Q_2

$$R_2 = \text{resistance of resistor } R_2$$

As it is possible to make the difference between the voltages V_{be1} and V_{be2} extremely small, the following relation can be obtained.

$$I_1 R_1 = I_2 R_2$$

By changing the above equation, it is obtained that

$$I_2 = \frac{R_1}{R_2} I_1$$

The above equation means that the current I_2 which is obtained by multiplying the constant current I_1 flowing through the load Z_1 by the multiplication factor R_1/R_2 flows through the loads Z_2 and Z_3 .

The direction containing the base-emitter junction of the transistors Q_1 and Q_2 is arranged in such a direction that the above voltages V_{be1} and V_{be2} compensate each other against the heat of their own generation and the variations of ambient temperature. Consequently, the variations of the voltages V_{be1} and V_{be2} due to the change of temperature cancel each other and no error will take place in the circuit.

Thus the connection of two transistors of mutually different polarities makes it possible to reduce the conversion errors compared with the case where only one transistor is used.

As stated above, from across terminals 1 and 4 and from across terminals 5 and 4 can be taken out respectively different voltage outputs $I_1 R_1 + V_{be1}$ and $I_2 R_2$.

Instead of the transistors Q_1 and Q_2 , if composite transistor circuits consisting of a combination of two or more transistors are employed, the conversion accuracy can be improved as the input impedance becomes high and the current amplification factor increases. In addition, as it is possible to make the collector current small in the first stage of the composite transistor circuit, the compensation for the voltage across the base and emitter against the self-generated heat and ambient temperature variation will be extremely improved.

FIG. 2 shows the method to connect the various components in case the polarities of constant current power source 11 in FIG. 1 are reversed.

FIG. 3 shows a connection diagram in case the power source E_2 is inserted between terminal 2 and the load Z_1 in FIG. 1. This type of connection is employed when it is more desirable to supply power separately from an inverter as the power source E_2 in such a common direct current power source system as impresses a direct current 24 v. voltage to individual instruments.

FIG. 4 shows an arrangement where loads Z_4 and Z_5 are connected in parallel in addition between terminals 4 and 5 in FIG. 1.

FIG. 5 shows arrangements where composite transistor circuits Q_{11} and Q_{12} are used respectively in place of the transistors Q_1 and Q_2 in the four-terminal network of FIG. 1.

The composite transistor circuits Q_{11} and Q_{12} are composed of transistors Q_{111} and Q_{112} and transistors Q_{121} and Q_{122}

respectively; and the collector currents of these composite transistor circuits shall be represented respectively by I_{in} and I_o . The collector current I_o consists of a collector current i_1 of the transistor Q_{121} and a collector current i_2 of the transistor Q_{122} .

When the current amplification factor of the transistor Q_{122} is expressed by β , the following relation can be obtained between the currents i_1 and i_2 .

$$\beta i_1 = i_2$$

Here, the difference between the base-emitter voltage drops of the transistors Q_{121} and Q_{122} is extremely small against the operation level and can be ignored; therefore the following relation can be established between the composite transistor circuits Q_{11} and Q_{12} .

$$I_{in}R_1 = (i_1 + i_2) R_2$$

From this equation can be obtained the current i_2 as shown below:

$$i_2 = \frac{I_{in}R_1}{R_2} - i_1$$

As this current is equal to βi_1 , the following equation can be obtained:

$$\frac{I_{in}R_1}{R_2} - i_1 = \beta i_1$$

The above equation can be changed as follows:

$$i_1(1 + \beta) = \frac{I_{in}R_1}{R_2}$$

$$i_1 = \frac{1}{1 + \beta} \cdot \frac{I_{in}R_1}{R_2}$$

From the above equations, i_2 can be obtained as follows:

$$i_2 = \frac{\beta}{1 + \beta} \cdot \frac{I_{in}R_1}{R_2}$$

Now, an output voltage V_o across terminals 4 and 8 is shown by the following formula:

$$V_o = (i_1 + i_2)R_2 + i_2R_3$$

If this formula is transformed by using the input current I_{in} , it is obtained that

$$\begin{aligned} V_o &= I_{in}R_1 + \frac{\beta}{1 + \beta} \cdot \frac{R_1}{R_2} I_{in} \cdot R_3 \\ &= I_{in}R_1 \left(1 + \frac{\beta}{1 + \beta} \cdot \frac{R_3}{R_2} \right) \end{aligned}$$

This means that by suitably selecting the magnitude of the resistors R_2 and R_3 , it is possible to obtain across output terminals 4 and 8 a voltage output larger than the voltage drop $I_{in}R_1$ due to the input current I_{in} .

We claim:

1. In an electric current converting circuit comprised of a pair of transistors having mutually different polarities, a pair of resistors connecting the emitters of the respective transistors to the bases of the other transistors, a constant current power source and a first load connected in series with a circuit composed of one of the transistors and one of the resistors, a second load connected together with a current power source and a third load in series with a circuit composed of the other of the transistors and the other of the resistors, and a separate current power source connecting the first load to the third load, characterized in that:

25 said two transistors are composed of composite transistor circuits; and
 30 a resistor is provided in series with the collector of one of the transistors in one circuit of the pair of said composite transistor circuits thereby to obtain a voltage output from a circuit containing said resistor.
